Patented Aug. 19, 1913.

UNITED STATES PATENT OFFICE.

JAMES R. HOPKINS, OF VINE GROVE, KENTUCKY, ASSIGNOR OF ONE-HALF TO
WILLIAM C. WOODS, OF VINE GROVE, KENTUCKY.

UMBRELLA.

1,070,894.

Specification of Letters Patent. Patented Aug. 19, 1913.

Application filed March 29, 1911. Serial No. 617,629.

To all whom it may concern:

Be it known that I, JAMES R. HOPKINS, a citizen of the United States, residing at Vine Grove, in the county of Hardin and 5 State of Kentucky, have invented new and useful Improvements in Umbrellas, of which the following is a specification.

An object of the invention is to provide an umbrella that can be quickly and easily 10 opened automatically by the operator.

For the purpose mentioned, use is made of a tubular staff having a spring disposed therein, one end of the spring being rigidly secured in the staff, the other end of the 15 spring being attached to a slideable sleeve constituting a handle, a series of ribs hingedly mounted at the upper end of the staff and hingedly connected by suitable rods and brace rods to a ring secured to the staff 20 so that the ribs can be folded around the staff when it is desired to close the umbrella, a runner movably mounted on the staff and having connection with the ribs and a connection between the said handle and the 25 said runner whereby when the handle is operated toward the lower end of the staff the ribs will be moved to closed position and when the handle is released from locking engagement with the lower end of the staff 30 the action of the spring will operate the said ribs, thus opening the umbrella.

Reference is to be had to the accompanying drawings constituting a part of this specification, in which similar characters of 35 reference denote corresponding parts in all the views, and in which—

Figure 1 is a side elevation of a portion of my umbrella showing the same in open position, parts being broken away to disclose 40 the underlying structure, and the cover being removed therefrom. Fig. 2 is a side elevation of a portion of my umbrella showing the same in closed position, parts being broken away. Fig. 3 is an enlarged vertical 45 sectional view showing the manner of securing the upper ends of the springs to the inner side of the staff.

Referring more particularly to the views, I provide a tubular staff 10 having a longitudinally extending slot 11 therein and rigidly secured to the upper end of the staff is a collar 12 having hingedly mounted thereon a series of ribs 13. Rigidly secured to the staff 10 is a ring 14 having hingedly 55 mounted thereon rods 15, the said rods 15

having their outer ends hingedly connected to auxiliary rods 16, said auxiliary rods being hingedly connected to the ribs 13 by pins 17. A nut or bearing 18 is secured to the inner side of the staff 10 and threadedly 60 engaging the said nut is a bolt 19, the said lower end of the said bolt being connected to a spring 20. Slidably mounted on the staff 10 is a runner 21 and hingedly mounted on the said runner are actuating rods 22 65 having their outer ends hingedly connected with the rods 15 at points 23, the spring 20 being secured at its lower end to the runner 21 by members 24 extending through the slot 11. 70

Mounted in the staff 10 and having the upper end thereof connected to the runner 21 is a connecting rod 25, the lower end of the said connecting rod being connected with a sleeve 26 slidably mounted on the staff 10 and provided with a handle 27, the said sleeve being provided with a slot 26^a. Mounted in the staff 10 at the lower end thereof is a locking spring 28 adapted to extend through a slot 29 in the staff 10 to 80 releasably lock the sleeve in position at the lower end of the staff 10 and adjacent the usual handle 30 thereof. 75

In the operation of my device, assuming that the umbrella is in closed position, when 85 it is desired to open the same, the locking spring 28 is pressed inwardly, thus disengaging the sleeve 26 with the locking spring and the contractile spring 20, being in tension when the umbrella is closed and having 90 a suitable contracting force, tends to assume its normal position, thus actuating the sleeve 26 to slide upwardly on the staff 10, thus also actuating the runner 21 to slide upwardly on the staff. As the runner slides 95 upwardly, the actuating rods 22 will be moved to force the ribs 13 outwardly and into open position, owing to the auxiliary rods 16 and the rods 15 having hinged connection with the actuating rods 22. When 100 it is desired to close the umbrella, the handle 27 is grasped and moved toward the handle 30 of the umbrella staff, thus moving the ribs 13 to closed position, and the umbrella will be retained in closed or locked 105 position by the locking spring 28 engaging the sleeve 26 in the slot 26^a thereof.

From the foregoing description it will be readily seen that by simply pressing the spring 28, the umbrella will be automati- 110

cally opened and the same can be quickly closed by reengaging the sleeve 26 with the spring 28.

Although for the purpose of describing my invention I have shown a particular construction, it will be understood that the scope of my invention is defined in the appended claim.

Having thus fully described the invention, what I claim as new, is:—

In an umbrella structure, the combination of a tubular staff having a longitudinal slot therein, a collar secured thereon, ribs pivotally secured to said collar, a ring rigidly secured to said staff and spaced below said collar, sectional stretcher rods pivotally connected with said ring and ribs, a runner slideable on said staff, actuating rods having pivotal connection with said runner and stretcher rods, a block fixedly secured within said staff at the upper end thereof, a second block slideable within said staff and rigidly connected with said runner through said slot, a longitudinally disposed rod arranged within said staff and having its upper end extending through said second mentioned

block and provided with an eye, a retractile spring disposed between said blocks and having one of its ends connected with said fixed block and its opposite end secured in said eye of the rod and operating to draw said runner upwardly on said staff to move said ribs to open position, said runner being adapted to abut against said fixed ring to limit its movement in one direction, a sleeve 35 slideable on said staff below said runner and rigidly secured to the lower end of said longitudinally disposed rod through said slot, means for lowering said sleeve to extend said spring and move said ribs to closed 40 position, said sleeve being provided with a slot, and means on the lower end of said staff for coöperation with said slot of the sleeve to retain said spring extended and the umbrella in closed position. 45

In testimony whereof I affix my signature in presence of two witnesses.

JAMES R. HOPKINS.
